UNITED STATES PATENT OFFICE

2,232,978

AMPULE OPENER

Arthur E. Smith, Los Angeles, Calif.

Application December 4, 1939, Serial No. 307,421

1 Claim. (Cl. 128—272)

This invention relates to ampule openers.

The general object of the invention is to provide a readily portable opener by means of which ampules containing corks, the contents of which are to be discharged into a vehicle in the ampule, may be opened.

A more specific object of the invention is to provide an ampule holder including a support and a handle portion and having a piercing member thereon adapted to be inserted in an ampule to remove a closure.

Other objects and the advantages of this invention will be apparent from the following description taken in connection with the accompanying drawing, wherein:

Fig. 1 is a side elevation of the ampule holder embodying the features of my invention;

Fig. 2 is a section taken on line 2—2, Fig. 1, and on an enlarged scale showing an ampule being inserted;

Fig. 3 is a view similar to Fig. 2 showing the ampule closure being removed;

Fig. 4 is an end view of the opener;

Fig. 5 is an end view of the ampule;

Fig. 6 is a view similar to Fig. 2 showing a modification;

Fig. 7 is a view showing the modified form with the closure removed;

Fig. 8 is a top plan view, partly in section, showing a further modification;

Fig. 9 is a side elevation, partly in section, showing the further modification with the ampule closure removed; and

Fig. 10 is a section taken on line 10—10, Fig. 8.

Referring to the drawing by reference characters I have shown my ampule opener which is indicated generally at 10 as comprising a body portion 11 and an end member 12. The body portion 11 is in the form of a hollow tube 13 which includes opposed notches 14 which form viewing apertures.

As shown the body includes a reduced outer portion 15 at one end which receives a flange 16 on the end member 12 with the parts held together in any desired manner as by brazing. The end member is provided with an aperture 17 in which a rod 18 is mounted and which preferably has a sharpened point 19 disposed within the body portion.

My opener is adapted for use for opening ampules such as the ampule 20 which has corks 21 therein provided with a chamber 22 for a drug 23. The inner portion of the chamber 22 is shown as closed by a trap door 24, while the outer portion of the chamber is closed by a diaphragm 25.

In use the opener is slipped over the end of the ampule as shown in Fig. 2 and is then pushed along the ampule to the position shown in Fig. 3.

As this is done the rod 18 first pierces the dia-

phragm 25 and then moves the closure 21 to open position so that the drug 23 will be discharged into the liquid 26 in the ampule.

In Figs. 6 and 7 I show a modification of the invention which is indicated generally at 30. In this modification the body 11' and the end member 12' are similar to the body 11 and end member 12 previously described. The rod 18' which dislodges the cork is, however, placed eccentric to the axis of the body 11' and end member 12' and is adapted to pierce a diaphragm 31 which forms an enclosure for a cavity 32 in a cork 33 arranged in a cylindrical ampule 34. A disk 35 made of any suitable material is arranged in any desired manner to form a closure for the cavity 32 in the cork.

The offset relation of the rod 18' assures that the disk 35 will be tilted when engaged by the rod 18'.

The use of the device disclosed in Figs. 6 and 7 is similar to that previously described.

In Figs. 8, 9 and 10 I show a modification of my invention wherein the ampule opener 40 is made from a flat blank as indicated by dotted lines 41 in Fig. 8, and includes a body portion 42 and an end member 43 with the end member bent at right angles to the body portion. A piercing member 44 is punched from the blank thus leaving a slot 45 in the body and end member.

The body portion is bent to an arcuate shape in cross section and may be provided with a surrounding collar 46 which may be held in place as by brazing.

The use of the device described in Figs. 8, 9 and 10 will be obvious from the previous description.

All of the parts comprising the opener are preferably made of metal, thus affording a device which can be readily sterilized and which is highly efficient for its intended purpose.

Having thus described my invention, I claim:

In an ampule opener, a sheet metal body, said body including an ampule engaging portion, said ampule engaging portion being arcuate in cross section at one end and merging into a portion which is plane in cross section at the other end, a collar surrounding the ampule engaging portion at the outer end of the arcuate portion, an end portion integral with the body and extending at right angles to the ampule engaging portion at the end having the flat cross section, a piercing member integral with the body and projecting from the end portion toward the opposite end of the ampule engaging portion, said piercing member being parallel to said ampule engaging portion and comprising a pointed portion and an enlarged base portion.

ARTHUR E. SMITH. 60
